UNITED STATES PATENT OFFICE.

CHARLES READ, OF CATONSVILLE, MARYLAND.

CARTON-SEALING MACHINE.

1,032,774.

Specification of Letters Patent. Patented July 16, 1912.

Application filed May 16, 1911. Serial No. 627,626.

To all whom it may concern:

Be it known that I, CHARLES READ, a citizen of the United States, residing at Catonsville, in the county of Baltimore and State 5 of Maryland, have invented certain new and useful Improvements in Carton-Sealing Machines, of which the following is a specification.

The purpose of this invention is to provide 10 a simple and effective device for sealing the ends of paper cartons, the construction and operation of which will be clear from the following specification, taken in connection with the accompanying drawings in which,—

Figure 1 is a side elevation of the machine; and, Fig. 2 is a vertical section taken centrally through the form carrier.

Referring to the drawing A indicates the 20 frame of the machine having a pair of uprights 1 between which is mounted a rotary form-carrier B comprising a shaft 2, journaled in said uprights, a hub 3 secured to the shaft and a series of spokes 4 having at 25 their ends forms 5 adapted to fit into the cartons. These forms are all alike, and equidistant from the axis of the carrier. Extending around the rear side of the member B, and carried by the frame A, is a support C consisting of a pair of plates 6 which extend about half way around the member B, at the sides of the forms 5, and the plates 30 composing this support are provided with bearings 7 in which are arranged rollers 8. As shown in the drawing, the bearings 7 are elliptical so that the rollers may have a slight radial movement with respect to the member B. The rollers are arranged close 35 together and the series of rollers extends 40 substantially concentric with the axis of the member B around the rear side of said member for a distance equal to nearly one half of its circumference. These rollers are adapted to bear against the ends of the 45 cartons on the forms 5 as the latter pass under the rollers. A band 9, preferably of 50 spring steel, extends around the outer sides of the entire series of rollers and presses the rollers firmly against the cartons.

In practice, the operator places a carton 55 upon the uppermost form 5^a at the front of the machine and cements and folds the end flaps and then moves the carrier in the direction of the arrow until the carton is carried under the uppermost rollers 8^a. An-

other carton is then placed upon the next form 5^b and its ends are cemented and folded and the carrier is given a partial rotation, as before, until the end of this carton is brought under the rollers at the top of the 60 machine. In the drawings the rollers are arranged to bear upon the cartons on six forms at one time and therefore it will be evident that each carton end will be pressed upon by the rollers during the time that the 65 operator is feeding six successive cartons to the machine. During this time the paste will set so that after a carton has passed from the lowermost roller 8^b the carton end will hold its shape. After passing from 70 the rollers each carton drops from its form through an opening 10 in the frame and into a suitable receptacle.

Any desired number of spokes and forms may be used. As the rollers may move 75 slightly on radial lines it will be evident that cartons with ends of varying thickness may pass by without becoming jammed against the rollers, as the latter and the spring band will yield outwardly opposite 80 the spokes if the carton ends are thick and may at the same time yield inwardly between adjacent spokes, the outward pressure at the spokes tending to straighten the band between the spokes. The forms are removably secured to the spokes and forms of different sizes may be used, as desired. 85

What I claim is:—

1. In a carton-sealing machine a rotatably mounted carrier having a plurality of 90 circumferentially arranged forms adapted to fit into the cartons, and means for pressing the ends of the cartons against said forms comprising a support, a series of rollers mounted in suitable bearings in said support, substantially concentric with the axis of 95 said carrier, said bearings permitting slight radial movement of the rollers, and an arcuate band adapted to yieldingly engage each of said rollers, said band having 100 its ends secured to the machine.

2. In a carton-sealing machine a rotatably mounted carrier having a series of 105 spokes and forms on the ends of said spokes adapted to fit into the cartons, a support extending adjacent the ends of a plurality of said forms at the rear side of the machine, an arcuate series of rollers journaled in said support so as to permit of slight radial movement of the rollers, and an arcu- 110

ate band adapted to yieldingly engage each of said rollers, said band having its ends secured to the machine.

3. In a carton-sealing machine a rotatably mounted carrier having a plurality of circumferentially arranged forms adapted to fit into the cartons, and means for pressing the ends of the cartons against said forms comprising a suitable support, a closely arranged series of rollers mounted therein substantially concentric with the axis of the carrier, the length of the series being greater

than the distance between adjacent forms, each roller being movable radially with respect to the carrier, and an arcuate band adapted to yieldingly engage each of said rollers, said band having its ends secured to the machine. ¹⁵

In testimony whereof I affix my signature, in presence of two witnesses.

CHARLES READ.
